(57) **CLAIM**

The ornamental design for a dispenser, as shown and described.

DESCRIPTION

FIG. 1 is a front perspective view of dispenser, showing my new design;

FIG. 2 is a front elevation view thereof;

FIG. 3 is a right side elevation view thereof, the left side being a mirror image thereof;

FIG. 4 is a front perspective view of a slightly modified embodiment of a dispenser, showing my new design;

FIG. 5 is a front elevation view thereof;

FIG. 6 is a right side elevation view thereof, the left side being a mirror image thereof;

FIG. 7 is a front perspective view of a slightly modified embodiment of a dispenser, showing my new design;

FIG. 8 is a front elevation view thereof; and,

FIG. 9 is a right side elevation view thereof, the left side being a mirror image thereof.

The broken lines shown in the drawings illustrate environmental structure and form no part of the claimed design.
